UNITED STATES PATENT OFFICE.

WILLIAM J. NESBITT, OF LOS ANGELES, CALIFORNIA.

HEEL-CUTTING APPARATUS.

1,170,178.

Specification of Letters Patent.

Patented Feb. 1, 1916.

Application filed August 23, 1915. Serial No. 46,975.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to heel cutting apparatus, more particularly to further improvements in the apparatus disclosed in my patents dated Sep. 1, 1914, Nos. 1109136, 1109137, 1109138, and 1109139.

The main object of the invention is to provide improvements whereby the construction is simplified and made more compact, practical and commercial, easy and convenient to operate, positive and quick in action; and which improvements cause better working of the apparatus, and enable the operator to do quicker, better, and more accurate work.

Other objects and the advantages of the invention will be apparent to those skilled in the art from a careful consideration of the following description of the preferred construction embodying the improvements, taken in connection with the accompanying drawings in which—

Figure 1 is a front elevational view of the apparatus; Fig. 2 is an enlarged cross sectional view taken on the line 2—2 of Fig. 8; Fig. 3 is an enlarged plan view of the shelf; Fig. 4 is a side elevational view of the apparatus; Fig. 5 is an enlarged broken view of a portion of the apparatus; Fig. 6 is an enlarged broken longitudinal sectional view through the handle of the shoe-heel clamping lever; Fig. 7 is an enlarged plan view of a portion of the apparatus; Fig. 8 is an enlarged plan view of a portion of the apparatus; Fig. 9 is a view like that of Fig. 8, with some parts broken away and others in changed position; Fig. 10 is a sectional view taken on the line 10—10 of Fig. 8; and Fig. 11 is an enlarged broken sectional view taken on the line 11—11 of Fig. 8.

The supporting frame or post 10 has thereon the shelf 11 secured in position by screws 12. A curved arm or extension 13 is provided at the upper part of the post 10 and has mounted thereon the adjustable holder 14 for the shaft 15 on which the

pulley 16 is loosely mounted. A band saw 17 passes around the pulley 16 and around the pulley 18 which is arranged fast on the shaft 19 which latter is mounted in the bearing 20 on the post 10. Any suitable devices may be provided to guide and hold the band saw 17 in adjusted position—those indicated at 21 and 22 being of well known construction and therefore needing no description.

The shelf 11 has thereon the dove-tail guide 23 on which is mounted the platform 24. Balls 25 arranged in raceways 26 are interposed between the shelf 11 and the platform 24 to render easy the movement of the platform on the shelf. On the top of the platform 24 is provided a dovetail guide 27 which extends at right angles to the guide 23 and has mounted thereon the table 28 which is provided with an extension 29 to the underside of which is secured by screws 30 the plate 31 which latter is adapted to make loose contact with the underside of the guide 27 which extends beyond the platform 24. The table 28 is operated to move it transversely of the platform 24 by means of the lever 32 which is mounted on the pivot 33 on the underside of the plate 31 and has its rear end pivotally mounted on the bracket 34 on the platform 24, and is provided with a handle 35 on its forward end portion. The lever 32 is locked in adjusted position by means of a projection 36 thereon which is adapted to fit in any one of the notches 37 in the arm 38 which is provided with a stop 39 at one end thereof and has its other end formed with an offset 40 whereby it is secured to the platform 24 by screws 41.

On the table 28 is mounted a plate 42 which has the forward end portion thereof mounted on a pivot 43 on the table 28. Posts 44 are provided on the rear end portion of the plate 42, and a hollow lever 45 having a handle 46 on its forward end has its rear end provided with teeth 47 and mounted on a pivot 48 between the posts 44. A projecting part 49 on the lever 45 is adapted to coact with a projecting part 50 on the plate 42 to clamp the heel of a shoe in position on the plate 42, and said lever 45 is locked in the clamping position by means of a pawl 51 which is arranged on a pivot 52 between ears 53 on one of the posts 44 and is adapted to engage the teeth 47 to prevent upward movement of the lever 45. To the pivot 52 is at

tached the crank arm 54 to which is connected the wire 55 which passes through the opening 56 in the lever 45 and is connected to the finger-operated lever 57 which latter has one end thereof mounted on the pivot 58 on the handle 46 and has its other end portion passing through a slot 59 in said handle, see Fig. 6. The platform 24 has thereon a plate 60 with suitable graduations 61 thereon, and the table 28 has thereon a pointer 62 to indicate the graduations. When the plate 42 is turned on the pivot 43 it is locked in adjusted position by means of the latch 63, which has one end mounted on the pivot 64 on the plate 42, and has on its other end a handle 65 and a projection 66 adapted to fit in any one of the notches 67 in the table 28. A wire 68 is connected to the latch 63 and passes through the opening 69 in the lever 45 and is connected to the finger-lever 70 which latter has one end mounted on the pivot 71 on the handle 46 and has its other end portion passing through the slot 72 in said handle. A stop 73 on the table 28 limits the movement of the plate 42 toward the band saw 17. On the lever 45 is mounted on the pivot 74 the angular bar 75 which is provided with the projection 76 adapted to bear against the forward part of a shoe heel and act as an abutment when the heel is being cut by moving it past the band saw 17. A handle 77 on the angular bar 75 is arranged in close proximity to the handle 46 so that both can be operated by the same hand, and a dog 78 which is mounted on a pivot 79 on the angular bar 75 is adapted to engage the teeth 82 on the arm 83 which is secured to the lever 45. A spring 81 on the angular bar 75 is adapted to press the dog 78 into engagement with the teeth 82, and said dog can be moved out of engagement with the teeth 82 by pressing down on the handle 80 on said dog.

A shaft 84 is mounted on the brackets 85 which are suitably secured on the underside of the shelf 11. Between the brackets 85 on the shaft 84 is arranged the sector 86 which extends into the slot 87 in the forward portion of the shelf 11 and is provided with teeth 88 adapted to mesh with teeth 89 on the underside of the platform 24. The shaft 84 can be turned by the handle 90 secured thereto. On the platform 91 at the rear of the post 10 is mounted the motor 92 which has fast on its shaft 93 the spur pinion 94 which latter meshes with the spur wheel 95 which is mounted fast on the shaft 19.

From the foregoing the manner of use and the advantages of the improved apparatus will be readily apparent to those skilled in the art. It will be seen that when the motor 92 is operated to drive the band saw 17, the finger-lever 57 may be pressed to effect disengagement of the pawl 51 from the teeth 47, whereupon the heel of a shoe to

be cut is placed between the projecting parts 49 and 50, and then the lever 45 is moved down to clamp the heel between said projecting parts. The lever 45 is automatically locked in clamping position by reason of engagement of the pawl 51 with the teeth 47. The handle 77 of the angular bar 75 may then be pressed down to cause the projection 76 to engage the forward part of the heel. Engagement of the dog 78 with the teeth 82 on the arm 83 automatically locks the angular lever 75 against movement. By pressing down on the handle 80 the dog 78 can be disengaged from the teeth 82. If a straight cut of the heel is to be made the plate 42 is moved to position against the stop 73 to have its side adjacent to the band saw 17 flush with the corresponding side of the table 28, whereupon the lever 32 is operated to move the table 28 transversely away from the band saw 17 until the pointer 62 indicates that one of the graduations 61 which corresponds to the amount it is desired to cut off from the heel. The handle 90 may then be moved upwardly to have the sector 86 operate the platform 24 and thereby effect movement of the table 28 and plate 42 thereon to move the heel past the band saw 17 to have the latter cut away a part of the heel. When it is desired to make an angular cut of the heel the finger lever 70 is operated to effect disengagement of the latch 63 from the teeth 67, and then the plate 42 is turned horizontally on the table 28 and thus moved away from the band saw until it makes the desired angle with the band saw, whereupon the finger lever 70 is released and the latch 63 again engages the teeth 67 and the plate 42 is thereby automatically locked in adjusted position on the table 28.

The construction which has been particularly illustrated and described admits of changes and modifications, wherefore the right is reserved to all such changes and modifications as do not depart from the spirit and scope of the invention which is defined in the appended claims.

I claim:

1. In heel cutting apparatus, the combination of a shelf, a cutter, a platform movably mounted on the shelf, a table transversely movable on the platform, a pivot on the table, a plate mounted on the pivot and adjustable horizontally on said pivot to dispose it at the desired angle to the cutter, and means carried by the plate for clamping the heel of a shoe.

2. In heel cutting apparatus, the combination of a shelf, a cutter, a platform movably mounted on the shelf, a table transversely movable on the platform, a graduated part on the platform, a pointer on the table, a pivot on the table, a plate mounted on the pivot and adjustable horizontally on said pivot to dispose it at the desired angle

to the cutter, and means carried by the plate for clamping the heel of a shoe.

3. In heel cutting apparatus, the combination of a shelf, a cutter, a platform 5 movably mounted on the shelf, a table transversely movable on the platform, a pivot on the table, a plate mounted on the pivot and adjustable horizontally on said pivot to dispose it at the desired angle to the cutter, 10 means carried by the plate for clamping the heel of a shoe, and means for locking the plate in adjusted position.

4. In heel cutting apparatus, the combination of a shelf, a cutter, a platform 15 movably mounted on the shelf, a table transversely movable on the platform, a pivot on the table, a plate mounted on the pivot, a lever having teeth thereon and pivotally mounted on the plate, coacting parts on the 20 lever and the plate for clamping the heel of a shoe, a pawl carried by the plate to engage said teeth to lock the lever in clamping position, and means for disengaging the pawl from said teeth.

25 5. In heel cutting apparatus, the combination of a shelf, a cutter, a platform movably mounted on the shelf, a table transversely movable on the platform, a pivot on the table, a plate mounted on the pivot, 30 means including a lever pivotally mounted on the plate for clamping the heel of a shoe, an angular bar pivotally mounted on the lever and having a part thereon adapted to engage the forward part of the heel, an arm 35 carried by the lever and provided with teeth, and a pivotally mounted dog on the

angular bar to engage the teeth to lock the angular bar when the latter is moved to engage the heel.

6. In heel cutting apparatus, the combination of a shelf, a cutter, a platform 40 movably mounted on the shelf, a table transversely movable on the platform and provided with notches, a pivot on the table, a plate mounted on the pivot and adjustable 45 horizontally on said pivot to dispose it at the desired angle to the cutter, a latch on the plate adapted to fit in said notches to lock the plate in adjusted position on the table, means for moving the latch out of the 50 notches, and means carried by the plate for clamping the heel of a shoe.

7. In heel cutting apparatus, the combination of a shelf, a cutter, a platform 55 movably mounted on the shelf, a table transversely adjustable on the platform, a pivot on the table, a plate mounted on the pivot, means for locking the plate in adjusted position on the table, means including a lever carried by the plate for clamping the heel 60 of a shoe, means for locking the lever in clamping position, an angular bar pivotally mounted on the lever and having a part thereon adapted to engage the forward part 65 of the heel, and coacting means on the lever and the angular bar for locking the latter when it is moved to engage the heel.

In testimony whereof, I have signed my name to this specification at Los Angeles, county of Los Angeles, State of California, 70 this 13th day of August A. D. 1915.

WILLIAM J. NESBITT.
